(57) **CLAIM**

The ornamental design for an organize tray for center console, as shown and described.

DESCRIPTION

FIG. 1 is a front, right side, top perspective view of an organize tray for center console showing my new design; FIG. 2 is a rear, right side, bottom perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; FIG. 9 is a cross-sectional view thereof as taken along the line 9-9 of FIG. 7; FIG. 10 is a cross-sectional view thereof as taken along the line 1 10-10 of FIG. 7; FIG. 11 is a cross-sectional view thereof as taken along the line 11-11 of FIG. 7; FIG. 12 is a cross-sectional view thereof as taken along the line 12-12 of FIG. 7; and, FIG. 13 is a cross-sectional view thereof as taken along the line 13-13 of FIG. 7. The broken lines depict portions of the organize tray for center console and form no part of the claimed design.
